UNITED STATES PATENT OFFICE

173,075

CLOCK DIAL

William Miller and Philip Levin, Chicago, Ill.

Application April 22, 1954, Serial No. 30,128

Term of patent 3½ years

(Cl. D42—1)

To all whom it may concern:

Be it known that we, William Miller and Philip Levin, citizens of the United States, residing at Chicago, county of Cook, and State of Illinois, have invented a new, original, and ornamental Design for a Clock Dial, of which the following is a specification, reference being had to the accompanying drawing forming a part thereof, in which:

Fig. 1 is a front elevational view of the clock dial, and

Fig. 2 is a top plan view.

We claim:

The ornamental design for a clock dial, as shown.
